UNITED STATES PATENT OFFICE

2,145,349

OILER

Friedrich Haacke, Machias, N. Y.

Application February 21, 1938, Serial No. 191,804

3 Claims. (Cl. 221—52)

The present invention relates to new and useful improvements in oilers and has for its primary object to provide, in a manner as hereinafter set forth, a device of this character embodying a pump of a novel construction and arrangement whereby the oil or other fluid may be conveniently discharged under air pressure.

Another very important object of the invention is to provide an air pressure oiler of the aforementioned character comprising a nozzle of such construction that the oil or other fluid may, if desired, be discharged in the form of a spray.

Other objects of the invention are to provide an oiler of the character described which will be comparatively simple in construction, strong, durable, highly efficient and reliable in use, compact, light in weight and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is a top plan view of an embodiment of the invention.

Figure 2 is a view in side elevation of the device with portions thereof broken away in section.

Figure 3 is a vertical sectional view, taken substantially on the line 3—3 of Fig. 2.

Figure 4 is a view principally in side elevation but partially in vertical section of the upper portion of the device, showing the spray nozzle in use.

Figure 5 is a detail view in vertical longitudinal section through the spray nozzle.

Figure 6 is an end view of the spray nozzle.

Figure 7 is a detail view in perspective of one of the spray nozzle discs.

Referring now to the drawings in detail, it will be seen that the reference numeral 1 designates a container of any desired capacity for the reception of the oil or other fluid. Screwed on top of the container 1 is a removable cap 2. Adjacent the cap 2, a filling cap 3 is provided on the container 1. Rising from the cap 2 is a neck 4 and threadedly mounted thereon is a removable packing nut 5. Mounted in the packing 5 and extending therethrough is a pipe 6. The construction and arrangement is such that the packing 5 is rotatable on the pipe 6 to permit said packing to be screwed on and off the neck 4. The pipe 6 extends to a point adjacent the bottom of the

container 1 and has mounted on its lower or intake end a suitable screen 7.

On the upper end of the pipe 6 is a housing 8 of suitable metal. Threadedly mounted in the housing 8 is a nipple 9 or the like 9 having a valve 5 seat 10 formed on its inner end. A gasket 11 prevents leakage at the joint between the nipple 9 and the housing 8. Threadedly mounted on the nipple 9 is a removable spout 12. Threadedly mounted on the free end portion of the spout 10 12 is a downturned, removable tip or nozzle 13.

Projecting from the housing 8 is a tube 14 which is aligned with the nipple 9. The reference numeral 15 designates a stem which extends slidably through the tube 14 into the housing 8 15 and which is provided, on its inner end, with a valve 16 which is engageable with the seat 10. As shown to advantage in Fig. 2 of the drawings, the valve 16 controls the oil passage in the nipple 9. A coil spring 17 in the housing 8 encircles 20 the stem 15 and is engaged with the valve 16 for yieldingly urging same toward the seat 10. A packing 18 is provided for the stem 15 where it emerges from the outer end of the tube 14.

Fixed on the upper portion of the container 1 25 is an angular bracket 19 of substantially the shape shown to advantage in Fig. 2 of the drawings. Pivotedly mounted on the bracket 19 is a trigger in the form of a bell crank lever 20 having one end operatively connected to the valve stem 15. 30 A handle 21 is provided beneath the bracket 19. It will be observed that one end of the handle 21 is fixed to the container 1 and that the other end of said handle is fixed to the bracket 19.

Mounted in the lower portion of the container 1 35 is an air pump which is designated generally by the reference numeral 22. The pump 22 comprises a horizontal barrel 23 which extends into the container 1 beneath the handle 21. A spring seated check valve 24 is provided in the discharge 40 end of the barrel 23. A removable cap 25 is threaded on the outer end portion of the barrel 23 and extending slidably through said cap is a rod 26. Mounted on the inner end of the rod 26 45 for reciprocation in the barrel 23 is a piston 27. Pivotedly mounted on the free end of the bracket 19 is a lever 28 the free end portion of which is operatively connected to the piston or plunger rod 26 of the pump 22. A coil spring 29 50 encircles the rod 26 and has one end engaged with the cap 25 and its other end engaged with the free end portion of the lever 28 for returning the piston 27 of the pump 22 to the position shown in Fig. 2 of the drawings. A cushioning 55

spring 30 is provided in the outer end portion of the barrel 23 for the piston 27.

It is thought that the operation of the device will be readily apparent from a consideration of the foregoing. By engaging certain of the fingers of one hand in the handle 21 and the palm of that hand with the lever 28, said lever may be conveniently actuated in a manner to operate the pump 22. On the inward stroke of the piston 27, air is forced under pressure from the pump barrel 23 into the container 1. When the pressure is removed from the lever 28 the spring 29 immediately returns said lever and the piston 27 to their former position ready for the next stroke. The spring 17 normally maintains the valve 18 in closed position, thus preventing the discharge of the oil. When it is desired to permit the discharge of the oil, the thumb of the hand holding the device is used to actuate the lever 20, thus opening the valve 18 against the tension of the spring 17. The oil in the container 1 is then forced by the air under pressure therein upwardly through the pipe 6 into the housing 8, then through the nipple 9, the spout 12 and the nozzle or tip 13. Of course, the discharge of the oil may be shut off when desired by simply releasing the bell crank lever 20. The cap 2 and the assembly thereon may be conveniently removed to permit cleaning the container 1 or for other purposes. The oil may be conveniently placed in the container 1 by simply removing the filler cap 3.

The reference numeral 31 designates generally a spray nozzle which may be substituted for the spout 12. The spray nozzle 31 comprises a conduit 32 which is adapted to be screwed on the nipple 9. Screwed on the forward end portion of the conduit 32 is a nipple 33 having mounted therein a screen 34. Threadedly mounted on the nipple 33 is a removable nut 35. Inner and outer discs 36 and 37, respectively, are mounted in the nut 35. Spacing gaskets 38 are provided for the discs 36 and 37. The outer disc 37 is provided with a single, centrally located port 39. The inner disc 36 is provided with a pair of discharge ports 40. The ports 40 are so arranged as to impart a whirling motion to the oil as it passes therethrough.

It is believed that the many advantages of an oiler constructed in accordance with the present invention will be readily understood and although a preferred embodiment of the device is as illustrated and described, it is to be understood that

changes in the details of construction and in the combination and arrangement of parts may be resorted to which will fall within the scope of the invention as claimed.

What is claimed is:

1. An oiler of the class described comprising a container for the reception of oil, a discharge spout mounted on said container and communicating therewith, a valve for controlling the discharge spout, a bracket mounted on the container, a lever pivotally mounted on said bracket and operatively connected to the valve, a pump mounted on the container for forcing air thereinto, another lever pivotally mounted on the bracket and operatively connected to the pump for actuating said pump, and a handle mounted on the container between said container and the second named lever.

2. An oiler of the class described comprising a container for the reception of oil, a discharge spout connected to the container and including a control valve, a pump mounted on the container for forcing air thereinto, a bracket mounted on the container, means on the bracket for operating the control valve, a lever pivotally mounted on said bracket and operatively connected to the pump for actuating said pump, and a handle mounted on the container adjacent the lever and the bracket.

3. An oiler of the class described comprising a container for the reception of oil, a screw cap removably mounted on the container, a pipe mounted in the screw cap and extending therethrough into the container, a housing on the outer end of said pipe, a nipple threadedly mounted in said housing and including a seat on its inner end, a discharge spout connected to said nipple, a tube projecting from the housing, a valve stem operable in the tube, a valve on one end of the stem engageable with the seat for controlling the flow of oil through the nipple, a pump mounted on the container for forcing air thereinto, means for operating the valve, and means for actuating the pump, the first named means including an angular bracket mounted on the container, and a bell crank lever pivotally mounted on said bracket and operatively connected to the valve stem, the second named means including another lever pivotally mounted on the bracket and operatively connected to the pump, and a handle mounted on the container between said container and the second named lever.

FRIEDRICH HAACKE.
